ELECTRIC RAZOR

Frederick K. Schwarz, Boston, Mass.

Application July 23, 1937, Serial No. 155,297

3 Claims. (Cl. 30—43)

This invention relates to a rotary razor driven by electric power, the general object of the invention being to provide a holder having means for holding a blade with its edges diverging to a member which has angle slots therein for receiving the beard, the edges of said slots and the blade producing a shearing cut.

This invention also consists in certain other features of construction and in the combination and arrangement of the several parts, to be hereinafter fully described, illustrated in the accompanying drawings and specifically pointed out in the appended claims.

In describing the invention in detail, reference will be had to the accompanying drawings wherein like characters denote like or corresponding parts throughout the several views, and in which:

Figure 1 is an elevation of the improved razor.

Figure 2 is a view looking toward the head end thereof.

Figure 3 is a view of a blade used with the device.

Figure 4 is a view looking toward the blade carrying end of the device, with the cup-shaped member removed.

Figure 5 is a longitudinal sectional view through the device.

Figure 6 is a view of the hollow shaft.

Figure 7 is a view of the inner shaft.

Figure 8 is a view, partly in section, of the drive shaft.

Figure 9 is a section on line 9—9 of Figure 5.

As shown in these views, the body of the device includes the parts 1 and 2, which are threaded together, the part 1 having a chamber 3 therein and the part 2 having a longitudinally extending bore passing therethrough in which is rotatably arranged the hollow shaft 4 by the anti-friction bearings 5. This hollow shaft is formed with an enlarged or elongated transversely extending head 6 having a substantially V-shaped recess 7 therein and a shaft 8 passes through the hollow shaft 4 and has a beveled elongated head 9 thereon for fitting in the recess 7 when the shaft 8 is placed in the shaft 4. A nut 10 is threaded on the inner end of the shaft 4 to hold the same in place, and the inner end of the shaft 8 has a reduced threaded part 11 terminating in the square part 12. A nut 13 is threaded on the part 11 and the square part 12 fits in a similar shaped socket 14 in the end of the shaft 15 which extends into the chamber 3 through the part 1, and this shaft is connected to an electric motor or the like. However, an electric motor may be carried by the part 1 and suitably connected with

the end of the shaft 8 to drive the two shafts 4 and 8.

A flexible blade, such as that shown at 16 in Figure 3, is adapted to be held between the heads 9 and 6 of the shafts 8 and 4, and as will be seen from Figure 5, when the blade is so held, it will assume a substantially V-shaped form. Projections 9' are carried by the head 9 and pass through holes 6' in the head 6. These projections also pass through holes 16' in the blade 16. A cap 17 is threaded on the enlarged outer end 2' of the part 2 and is held in adjusted position by the lock nut 18. The cap has a flat outer face of circular shape with a short beveled part 19 at its circumference and an annular row of 15 slots 20 is formed in the periphery of the flat part of the cap and extends into the beveled part, these slots being angularly arranged so that their edges will produce with the edges of the blade 16, a draw cut on the hairs extending through the 20 slots.

As will be seen, the device uses a commercial safety razor blade and thus utilizes a cutting edge instead of a clipping edge, and this results in a cleaner and faster shave. The slots should be 25 milled at the most favorable angle for efficient cutting, it being understood that the cap is adjusted on the head 2' until it makes sufficient contact with the blade to produce an efficient cutting action.

It is thought from the foregoing description that the advantages and novel features of the invention will be readily apparent.

It is to be understood that changes may be made in the construction and in the combination and arrangement of the several parts, provided that such changes fall within the scope of the appended claims.

What I claim is:

1. A razor of the class described comprising a 40 body, a rotary shaft journaled in the body, means for attaching a normally flat double edge blade to the outer end of the shaft, said means flexing the blade into substantially V-shape in cross section throughout the length of the blade and 45 a cap adjustably connected with the body and having a flat outer face having angle slots therein for producing with the cutting edges of the blade a shearing cut.

2. A razor of the class described comprising a 50 body, a hollow shaft journaled therein and having one end extending from one end of the body, a head on said end of the shaft having a substantially V-shaped recess therein, a second shaft passing through the hollow shaft, said 55

second shaft having a beveled head thereon fitting in the recess, the two heads acting to clamp a blade between them with the blade assuming a substantially V-shape, means for holding the shafts in place, means for rotating the shafts, a cap threaded on that end of the body from which the head of the first shaft projects, said cap having a flat central portion over the inner face of which the blade operates, and said cap having an annular row of angle slots at its periphery.

5 3. A razor of the class described comprising a body, a hollow shaft journaled therein and having one end extending from one end of the body, a head on said end of the shaft having a substantially V-shaped recess therein, a second shaft

10 15

passing through the hollow shaft, said second shaft having a beveled head thereon fitting in the recess, the two heads acting to clamp a blade between them with the blade assuming a substantially V-shape, means for holding the shafts in place, means for rotating the shafts, a cap threaded on that end of the body from which the head of the first shaft projects, said cap having a flat central portion over the inner face of which the blade operates, said cap having an annular row of angle slots at its periphery, the cap having a beveled part connecting its rim to the flat part and the slots extending into said beveled part.

FREDERICK K. SCHWARZ. 15
